(57) **CLAIM**

The ornamental design for a floor cleaning pad, as shown and described.

DESCRIPTION

FIG. 1 is a perspective view showing the new design for a floor cleaning pad. The vertical striped lines indicate that the upper face of the pad is red, and the other face of the pad is blue.

FIG. 2 is a side view of the floor cleaning pad.

FIG. 3 is a top view of the floor cleaning pad; and, FIG. 4 is a bottom view of the floor cleaning pad.

The drawing is lined for color.

The features indicated by broken lines are for illustration purposes and are not an essential part of the design.
